UNITED STATES PATENT OFFICE.

STEPHEN P. RUGGLES, OF BOSTON, MASSACHUSETTS.

PRINTING-PRESS.

Specification of Letters Patent No. 23,951, dated May 10, 1859.

To all whom it may concern:

Be it known that I, STEPHEN P. RUGGLES, of Boston, in the county of Suffolk and State of Massachusetts, have invented certain new and useful Improvements in Printing-Presses; and I do hereby declare the following to be a full, clear, and exact description of the construction and operation of the same, reference being had to the accompanying drawings, making a part of this specification, in which—

Figure 1 represents a perspective view of a hand printing press, with my invention applied. Fig. 2 represents a vertical section 15 through the press and Figs. 3 and 4 represent details of the press which will be specially referred to in the description.

Similar letters of reference where they occur in the separate figures denote like parts 20 in all of them.

In hand printing presses, it is necessary to have as much as half an inch rise and fall to the platen, to conveniently run in the sheets, as with less rise and fall, owing to the frisket 25 being repasted, and perhaps marked a little, as also several blankets being used, the tympan will not lie down perfectly snug, and would rub in running under the platen, and have a tendency to slur the sheet, before the 30 impression is given, unless there is plenty of room. The pressman, too, cannot pull upon a bar or lever of a hand press more than one quarter around, or one quarter of a full revolution, and if, therefore, a screw with a 35 coarse enough thread be used, to give the required rise and fall of the platen, by a quarter turn or revolution it would not be powerful enough, with the strength of one man, to give the impression, and if, on the other 40 hand, a fine threaded screw be used, the necessary motion of the platen in a vertical direction cannot be had—so that with one screw it is impossible, by a quarter turn of the bar, which is about as far as a pressman 45 without leaving his stand can move it, to get the rise and fall of the platen, and the power too—one being gained or lost at the expense of the other.

Now my invention consists in so combining 50 and using two screws, both operated by one motion of the bar or lever, but at different times—one screw being coarse threaded and the other fine-threaded, as that the former shall effect the rising and falling, mainly, of 55 the platen, while the latter comes into action when the impression is to be taken, or when

the power is required, and the coarser screw has exhausted itself. And my invention further consists in running in the bed on inclined ways, in order to give a much greater 60 distance between the bed and platen when it starts to run under than there is when it is run under as far as it is to go, and ready for the impression. And it also consists, in the means of regulating the impression by 65 means of a set screw or its equivalent device that connects the spring (which is made fast to the coarse screw) to the bar or lever that gives the impression.

To enable others skilled in the art to make 70 and use my invention, I will proceed to describe the same with reference to the drawings.

A, represents the frame of the press, upon which are placed two inclined ways C C, for 75 the bed B to run out and in upon. The object in inclining the ways C, C, so that their outer ends shall be lower than those under the platen, is that the distance between the bed and platen D, shall be greater when the 80 bed starts to run under than when it is run under—or, in other words that the bed as it is run under the platen shall approach the platen continually until it reaches its position, thus facilitating the running under of 85 the sheets, and the parts connected with it. The position of the bed, form, etc., when run out on the ways, is shown in red in Fig. 2, while their position when under the platen is shown in black lines. 90

D, is the platen of the press, to which the shaft E is affixed—the upper end of which carries the rod or lever F.

G are guides attached to the sides of the platen, and moving through openings in the 95 enlarged portions H of the yoke I, which contains the several parts of the press. The tops of these guide rods G, are furnished with coiled springs a to raise the platen, after the lever or bar F, is turned back, and 100 to release the bed.

In the hub J, which occupies a central position in the yoke I, there is cut a coarse female screw thread, in which runs a sleeve, 105 hollow screw shank b, the interior bore of said sleeve, boss, or screw shank having a fine screw thread cut in it which receives the male thread on the shaft E.

c, is a strong helical spring, the inner end of which is permanently fastened, as at 2, 110 to the screw boss, or sleeve b, while its outer end is fastened as at 3, to the lever F, by

means of an adjustable clamp *d*, and set screw *e* by which the said spring *c*, may be practically lengthened or shortened, as it may be desired to have more or less sweep of the lever, or a greater or less rise and fall of the platen.

K, is a stop which defines the limit of motion of the lever *F*, when taking the impression.

- 10 The object of the two screws, viz. the coarse and fine one, both actuated by the lever *F*, is that a slight motion of the lever *F*, say a quarter turn, will raise the platen sufficiently high from the bed, to allow the 15 form, frisket, sheet, blankets, and the appliances generally used in connection therewith, to freely run under without slurring the sheets, while the fine screw comes into action just at the time when the greater 20 power is required to take the impression. In this construction, and in practice, it is found that the coarse screw will run out, and the fine screw into, action, and vice versa, without being able to detect by the 25 operation of the machine when the cessation of one, and the action of the other begins.

The operation is obvious. The lever *F*, and fine screw *E*, being permanently as it were one piece, when the lever *F* is first 30 turned it communicates its motion to the coarse screw *b*, by means of the spring *c*, which moves the coarse screw downward until the resistance on the platen *D* becomes so great as to arrest the motion of said coarse 35 screw;—and then by continuing the movement of the lever *F*, the fine screw *E* commences working, winding up the spring *c*, and completes the taking of the impression. I thus avail myself of the coarse screw 40 for speed or extent of motion and the fine screw for power, one running into the other, or one ending and the other beginning their action, just where motion or power is required. By shifting the screw clamp the 45 action of the two screws may be adjusted so that one shall cease and the other begin where it is desirable that they should do so.

Now, I have described and shown this invention as applied to a hand press, but I do 50 not limit it to such presses alone, as it is equally applicable to power presses, fly presses, bookbinders' gilding presses, and embossing and copying presses, or any other presses where an impression is to be made, 55 taken or received, the principle involved being that of a platen moved to or from a bed, or a bed moved to or from a platen with varying speed and power, viz. speed when power is not required, and power when it is 60 required, when effected by a coarse and fine

screw working together in a manner as herein described.

I am of course aware that a lever, or system of levers, may be so arranged as that they will sacrifice speed to power or vice versa, by bringing them more or less into line with the resistance, or by changing their fulcra, but my invention is entirely different from such, and is limited to the use of screws having coarser and finer threads, through which the speed and power are both achieved, and which can be put into a neat compact form where levers could not be used at all.

I have also shown a coiled spring *c* for clamping the outer screw and lever, so as to cause the lever to turn the inner or finer threaded screw. Now the motion of the inner screw may be increased, that is its number of turns, when desirable to do so, by interposing a spur and pinion that will come into action when a greater number of turns is wanted, or the number of turns may be diminished by properly apportioned gearings in a similar manner. All these modifications of the operation of the two screws are obvious to a mechanician. And instead of two screws only, more may be operated by substantially the same connections that will exhaust one and bring the next one into action. Instead of the screws all being one within the other, they may be arranged along the shaft, at more than one point, and still effect the object.

Having thus fully described the nature and object of my invention what I claim therein as new, and desire to secure by Letters Patent is—

1. The combination of two screws having different sized threads, and operating together substantially as described, to give a greater motion to a platen or its equivalent, at one time, and more power at another time, as may be desired.

2. I also claim connecting two such screws together and to the lever or bar that actuates them by a strong helical spring that, by being wound up becomes a clamp, so as to put the two screws in action—one after the other, substantially as herein described.

3. I also claim running out the bed of the press on inclined ways, for the purpose of increasing the distance between the bed and platen, which makes a better entrance for the frisket, blankets, sheet, form, &c., by affording more space, when they are being run under the platen, as described.

STEPHEN P. RUGGLES.
